UNITED STATES PATENT OFFICE.

GEORGE E. COUTANT, OF PERU, INDIANA, AND ARTHUR E. LEHMANN, OF ST. CHARLES, MISSOURI.

RAILROAD-CAR-BUFFER CONSTRUCTION.

1,270,791.

Specification of Letters Patent.

Patented July 2, 1918.

Application filed June 16, 1917. Serial No. 175,139.

To all whom it may concern:

Be it known that we, GEORGE E. COUTANT and ARTHUR E. LEHMANN, citizens of the United States, and residents, respectively, 5 of Peru, in the county of Miami and the State of Indiana, and of St. Charles, in the county of St. Charles and State of Missouri, have invented a certain new and useful Improvement in Railroad-Car-Buffer Con- 10 structions, of which the following is a full, clear, concise, and exact description, reference being had to the accompanying drawings, forming a part of this specification.

This invention relates to improvements in 15 railroad car buffer construction.

Heretofore, it has been the general practice in connection with buffers of railroad cars, to support the buffer plate with the diaphragm face plate carried thereby, on 20 the outer ends of two relatively small stems. Due to the almost constant movement of the buffer plate when the cars are in service, the said side stems wear out very rapidly thereby permitting the buffer plate and 25 diaphragm face plate to sag, in addition to requiring frequent repairs. Furthermore, the almost constant movement of the side stems which have to carry the load, results in a noise which is disagreeable especially to 30 the passengers on passenger cars.

The object of our invention is to provide a buffer arrangement for railroad car equipment wherein the buffer plate is supported independently of any side or center stems, 35 the construction being such that a large wearing area is provided between the buffer plate and the buffer beam to thereby decrease the rate of wear, to prevent sag, to minimize noise and simplify the application 40 and removal of buffer.

More specifically, the object of our invention is to provide a buffer arrangement of the type above indicated wherein the buffer plate is provided with an inward extension 45 approximately the full width of the buffer plate, which extension slides in a corresponding recess provided in the buffer beam and by which the buffer plate is slidably supported.

50 In the drawings forming a part of this specification, Figure 1 is a horizontal sectional view, taken just above the floor level of a car, and showing, in full lines, the normal position of the buffer plate. The dotted 55 lines indicate one of the positions assumed

by the buffer plate when the car is coupled up with an adjacent car and is passing around a curve. Fig. 2 is a central, longitudinal, vertical, sectional view, taken substantially on the lines 2—2 of Fig. 1. Fig. 60 3 is a view similar to Fig. 2, but taken on the lines 3—3 of Fig. 1. Fig. 4 is a transverse, vertical, sectional view, taken substantially on the line 4—4 of Fig. 1. And Fig. 5 is a view similar to Fig. 1, illustrating another embodiment of the invention.

Referring to the construction illustrated in Figs. 1 to 5 inclusive, 10 denotes the platform of a car which, in general construction, is substantially the same as those 70 now in service. Said platform 10 is provided with a central recess 11^a in which is located the buffer mechanism proper 11. On each side of the buffer mechanism is located a side stem 12 which is slidably 75 mounted in suitable partitions 13—13, each side stem being under the control of a spring 14 in the usual manner. A central or main buffer stem 15 is provided which co-operates with the front follower 16 of the 80 buffer mechanism.

The platform 10 is provided at its outer or front edge with a buffer beam, designated generally by the references 17 and 17^a, the former indicating the lower section of the 85 buffer beam and the reference 17^a the upper section thereof, said sections 17 and 17^a being separated by a horizontal recess 18 which extends transversely of the buffer beam and is provided for the purpose hereinafter described. The buffer beam is round on its forward face, as indicated at 19, in the usual manner.

The buffer plate is indicated generally by the reference A and, as shown, comprises a buffer plate portion 20 proper and an inwardly or rearwardly disposed extension 21, said extension 21 being of a width approximating the full width of the buffer plate and slidable within said recess 18 formed in the buffer beam. Said extension is integral with the plate 20 and along its rear face is provided with a central projection 22 against which engages the central buffer stem 15. At either side of the projection 22, said extension 21 is provided with faces 23 against which normally bear the forward ends of the side stems 12 and in this connection, it will be noted that the outer ends of all the stems are normally dis- 110

posed within the buffer beam and do not project beyond the buffer beam, and consequently have no function in supporting the weight of the buffer plate and associated parts. The buffer beam is provided with suitable wear plates 24, 25 and 26 for the extension 21 and the stems (see Figs. 2 and 4). Also, the rear face of the extension 21 is provided with suitable wear plates 27, 10 28 and 29 for engagement with the side and central buffer stems, as will be clear from an inspection of Fig. 1.

In order to retain the buffer plate in position and also to permit the necessary sliding and swinging movements thereof, said extension is provided with three slots 30, 31 and 32. The slot 30 is located at the center of the extension 21 and extends parallel to the center line of the car. Extending 20 through said slot 30 is a heavy pin 33 carried by the buffer beam and which is held in position by any suitable means such as a bolt 34. The slot 30 is of the same width throughout its entire length, said width 25 corresponding to the diameter of the pin 33 so that the buffer plate does not have lateral movement with respect to said pin 33. Each of the other slots 31 and 32 is tapered from rear to front, as clearly indicated in Fig. 1, and extending through 30 said slots are other pins 35—35, the latter being also supported in the buffer beam and held in position by bolts 34. The diameter of the pins 35 corresponds substantially to 35 the minimum width of the slots 31 and 32 so that the buffer plate when swinging will not bind and the necessary freedom of movement is permitted while at the same time preventing undesirable lateral movement of 40 the buffer plate. ....

In order to reduce the amount of metal required, the extension 21 may be recessed, as indicated at 36—36. The plate portion 20 proper is provided with an upper rearwardly extending horizontal flange 37 which is adapted to slide over a horizontal face 38 on the upper portion of the buffer beam and acts as a support for the usual foot plate 40 which slides beneath the usual floor 45 plate 41 carried by the buffer beam.

From the preceding description, it will be seen that the entire weight of the buffer plate and associated parts, is supported by the extension 21 which slides with a smooth 55 fit in the recess provided in the buffer beam and consequently the side stems are relieved of all load and are employed merely for the purpose of forcing the buffer plate out to normal position and preventing improper swinging movements thereof. The 60 pin and slot connections between the buffer plate and the buffer beam permit the necessary movements of the buffer plate while at the same time forming suitable guides 65 for the buffer plate. On account of the ex-

tended surface engagement between the extension 21 and the buffer beam, wear is reduced to a minimum as is also the noise resulting from the constant movements of the buffer plate.

In the construction illustrated in Fig. 5, the arrangement of buffer plate, buffer beam, buffer mechanism and central buffer stem is substantially the same as that described in the other figures. In this construction, 75 however, the side stems are omitted and in order to maintain the buffer plate in proper position, the center stem 115 for the buffer mechanism has rockably mounted thereon at its outer end a spring holding band 50 80 through which extend bowed springs 51, the latter at their ends bearing against the rear face of the buffer plate extension 121 and by which the latter is normally forced outwardly and held in proper position. The 85 inner projection 122 on the extension 121 is normally spaced from the front face of the band 50 so that the springs 51 will be flexed and under tension when the cars are coupled. It is believed the construction in operation will be understood without further description in view of the more detailed description given of the construction illustrated in Figs. 1 and 4.

We claim:

1. In car construction, the combination with a buffer beam having a central, horizontal recess extending transversely of the beam and open along its forward edge, of a buffer plate having a central, horizontal extension on the inner side thereof, said extension being slidable within said recess and forming the support for the buffer plate, pin and slot connections between said extension and the buffer beam for limiting the outward movement of the buffer plate and at the same time permitting the necessary sliding and swinging movement thereof, and a buffer for yieldingly resisting inward movement of the buffer plate.

2. In car construction, the combination with a buffer beam having a single, elongated horizontal recess extending transversely thereof and open along its forward edge, of a buffer plate having a corresponding horizontal extension on the inner side thereof slidable within said recess, said extension forming the sole support for the buffer plate, means limiting the outward and lateral movement of the buffer plate 120 with respect to the buffer beam, a buffer mechanism, and spring-operated means acting against the lateral portions of said extension and within the buffer beam for holding the buffer plate in normal position.

3. In car construction, the combination with a buffer beam having a transversely extending horizontal recess in its forward face, of a buffer plate having a transversely extending flange on its inner face slidable 130

within said recess and forming the support 5 for the buffer plate, means for limiting the outward movement of the buffer plate with respect to the buffer beam, buffer mechanism, and spring-controlled slidable side stems engaging the rear edge of said flange at either side of the center, the outer ends of said side stems being always disposed within the buffer beam.

10 4. In car construction, the combination with a buffer beam having a horizontally extending recess in its forward face, of a buffer plate having an integral extension on its inner side slidably mounted within said 15 recess, said extension forming the support

for the buffer plate, said extension being provided with slots, pins carried by the buffer beam extending through said slots and adapted to limit the outward movement of the buffer beam while at the same time permitting sliding and swinging movements thereof, a buffer mechanism, and means for yieldingly pressing the lateral portions of said extension to maintain the buffer plate in proper position. 20

In witness that we claim the foregoing, we have hereunto subscribed our names this 26th day of May, A. D. 1917.

GEORGE E. COUTANT.
ARTHUR E. LEHMANN.
